United States Patent Office.

RICHARD SMITH, OF PHILADELPHIA, PENNSYLVANIA, ASSIGNOR TO MAC-KELLAR, SMITHS & JORDAN, OF SAME PLACE.

Design No. 4,560, dated January 3, 1871.

DESIGN FOR TYPE.

The Schedule referred to in these Letters Patent and making part of the same.

To all whom it may concern:

Be it known that I, RICHARD SMITH, of the city and county of Philadelphia, Pennsylvania, (assignor to MacKellar, Smiths & Jordan,) have invented and produced a new and original Design for Printing-Type, of which the following is a specification.

The nature of my design is fully represented in the accompanying typographic impressions, to which reference is made.

I claim as my invention—

The design for printing-type, as shown.

Witnesses: RICHARD SMITH.
